[57] CLAIM

The ornamental design for a fishing lure head, as illustrated and described.

DESCRIPTION

FIG. 1 is a right side elevational view of my new lure head, which is a mirror image of the left side elevational view;

FIG. 2 is a front end view of the lure head;

FIG. 3 is a rear end view of the lure head;

FIG. 4 is a right side elevational view of another embodiment of the lure head, and is a mirror image of the left side elevational view;

FIG. 5 is a front end view of the lure head of FIG. 4;

FIG. 6 is a rear end view of the lure head of FIG. 4; and

FIG. 7 is a cross-sectional view of the lure head of FIG. 4 on line 7—7.

FIG. 1

FIG. 2

FIG. 3

FIG. 4

FIG. 5

FIG. 6

FIG. 7
